UNITED STATES PATENT OFFICE.

CLARENCE C. SIBLEY, OF PERTH AMBOY, NEW JERSEY, AND GEORGE A. LUTZ, OF NEW YORK, N. Y.

INCANDESCENT-LAMP SOCKET.

No. 833,556.

Specification of Letters Patent.

Patented Oct. 16, 1906.

Application filed June 5, 1903. Serial No. 160,151.

To all whom it may concern:

Be it known that we, CLARENCE C. SIBLEY, a resident of Perth Amboy, Middlesex county, New Jersey, and GEORGE A. LUTZ, a resident 5 of New York, borough of Brooklyn, State of New York, citizens of the United States, have invented certain new and useful Improvements in Incandescent-Lamp Sockets, of which the following is a specification.

10 The object of our invention is to provide improved means for insulating the lead-in wires or conductors of an incandescent-lamp socket from the operative parts and from the metallic shell and cap covering the same; 15 and to this end we provide an insulating-lining for the metallic cap that has an integral apertured extension passing through an opening in the cap and means for securing the lining to the cap.

20 Reference is to be had to the accompanying drawings, forming part hereof, wherein—

Figure 1 is a side view of a socket embodying our invention. Fig. 2 is a central section through the cap and its lining. Fig. 3 is a side 25 view of the insulating-lining. Fig. 4 is a sectional view of the cap. Fig. 5 is a detailed view of the ring for holding the cap and lining together. Fig. 6 is a central section showing modified means for holding the cap and 30 lining together, and Fig. 7 is a plan view thereof.

Similar numerals indicate corresponding parts in the several views.

In the drawings the numeral 1 indicates a shell or casing adapted to inclose the operative parts of an incandescent-lamp socket of any suitable construction, and 2 indicates a cap adapted to be connected to the shell by any suitable or well-known means, as by a 35 pin-and-slot connection, as at 3, 4.

At 5 is indicated a lining for cap 2, which is to be made of any suitable insulating material, such as rubber or porcelain, and the lining 5 has an extension or projection 5^a of 45 similar material, shown as made in one piece or integral with lining 5, and at 5^b the lining and its projection 5^a are shown provided with an aperture or bore leading into cap 2. The

cap 2 is provided with an opening 2^a, through which the projection 5^a passes. The lead-in 50 wires or conductors pass through the bore 5^b, and by means of the lining 5 and projection 5^a are insulated from cap 2. We have shown means for detachably connecting the lining 5 with cap 2, as follows: On the exterior of projection 5^a, close to the outer surface of cap 2, is a groove or recess 5^c, in which a split ring 6 fits, as shown in Figs. 1 and 2. The ring 6 by engaging cap 2 prevents projection 5^a from being pulled through opening 2^a, and as lining 5 is within cap 2 the lining and its projection are securely attached to the cap. 55

In Fig. 6 the ring 6 is interposed between lining 5 and cap 2, and in this case the lining is shown provided near its lower edge with a 65 recess 5^d, and the cap 2 has an internal groove or recess 2^b, the ring 6 fitting in said grooves or recesses, and thereby holding said lining within the cap. It will be also understood that by allowing the lining 5 to rest upon the 70 usual base within the shell 1 the apertured projection 5^a will be prevented from slipping inwardly through the aperture 2^a in cap 2, while the latter is held upon shell 1, if the ring 6 should be removed. 75

By means of our improvements the lining 5 and its projection can be readily attached to and removed from cap 2, and the lining and its projection afford perfect insulation between the cap and the lead-in wires and 80 their operative parts.

Having now described our invention, what we claim is—

1. An incandescent-lamp socket having a cap provided with a top opening, a lining 85 within said cap provided with an apertured projection passing through said opening, and a ring engaging the cap and serving to hold the lining and its projection in position, substantially as described. 90

2. An incandescent-lamp socket provided with a cap having a top opening and a lining of insulating material provided with an apertured projection passing through said opening, said projection having a groove or recess 95 without the cap, and a ring located in said

groove or recess adapted to engage the cap to hold the lining and its projection in position, substantially as described.

3. In an incandescent-lamp socket the cap provided with an opening in its top and an insulating-lining having an apertured insulating projection passing through said opening, and means connected with the cap for

preventing said projection from slipping inwardly through the aperture in the cap, substantially as described.

CLARENCE C. SIBLEY.
